UNITED STATES PATENT OFFICE.

WILLIAM S. PRIDE, OF OAKLAND, CALIFORNIA.

CORNER FOR PLASTERING.

1,097,935.

Specification of Letters Patent. Patented May 26, 1914.

Application filed December 22, 1913. Serial No. 808,102.

To all whom it may concern:

Be it known that I, WILLIAM S. PRIDE, a citizen of the United States, residing at Oakland, in the county of Alameda and State of California, have invented new and useful Improvements in Corners for Plastering, of which the following is a specification.

This invention relates to a device for forming and protecting the corners of plastering for walls.

It consists of a rigid structure, preferably of metal, fitting the corner formed by the meeting angles of the wall, and having projections from each of the angular portions substantially at right angles thereto, said projections forming the gage for the thickness of the plaster on the contiguous walls, a space for the plaster interior to said projections, and perforations through which the plaster may pass to form an interlock and continuous bond.

My invention also consists in the combination of parts and details of construction which will be more fully explained by reference to the accompanying drawings, in which—

Figure 1 is a detail perspective view of the corner plate. Fig. 2 is a horizontal section of a plastered corner showing the device applied.

Various plastering corners or angle beads have been employed for the meeting angles of plastered corners, the plaster being often separated at these angles by the construction of the beads. In my invention I have so designed the angle or corner pieces that they will fit into the wood or other work of the corner, and they are provided with gages projecting toward, but separated from, each other so that the plaster may be applied and leveled to the gages and continued on to form a corner between these gages, and also to fill the intervening space and form a perfect lock.

As shown in the drawings, the parts A—A may be of metal or other suitable material bent at an angle to fit the corner of the building, as shown at 2. These parts have projections 3 standing at right angles and approaching each other, but leaving a space between. These projections or gages may be made in forming the angle piece by folding the portions A by means of any suitable former and as plainly shown in the draw-

ings. The parts A and the gage beads or projections are also perforated, as shown at 4, so that the plaster, when spread upon the walls, may be admitted through these perforations and form a perfect bond.

It will be seen that by the construction here shown a rectangular space is formed between the angle of the sides A and the projecting strips or gages 3, and that when the mortar is spread upon the walls A, it also passes into this rectangular space thereby filling it. The edges of the beads 3 form a gage to which the level of the mortar is brought, and the mortar being continued beyond these beads forms the proper angle within the rectangle and from the contained mortar. As the perforations pass through the parts A and the beads 3, and also through the interior rectangle, it will be seen that when the mortar has been spread it will all be united and when set forms a very firm and solid corner which will not be liable to crack after having set.

I wish it understood that various modifications may be made in the device without departing from the principle of the invention.

Having thus described my invention, what I claim and desire to secure by Letters Patent is—

1. A corner piece and gage for plastering consisting of a metal sheet bent to form a body having a pair of sides which meet in a substantially right angle, each of the sides of said body having an intermediate part which is folded over upon itself to provide a projection which extends at substantially right angles to the side and is located at points between the outer end of the side and the angle formed by the meeting inner ends of the sides, said angle being for engagement with a corner of the structure to which the gage is applied, there being a free open space between the entire inner faces of said projections to allow plaster to be engaged with said inner faces of said projections throughout the areas of same and also with the inner faces of the sides at the portions of said sides between the projections.

2. A corner piece and gage for plastering consisting of a metal sheet bent to form a body having a pair of sides which meet in a substantially right angle, each of the sides of said body having a substantially

right angular projection located at points between the outer end of the side and the angle formed by the meeting inner ends of the sides, the outer face of said angle being for engagement with a corner of the structure to which the gage is applied, there being a free open space between the entire inner faces of said projections to allow plaster to be engaged with said inner faces of said projections throughout the areas of same and

also with the inner faces of said sides where same meet in said angle.

In testimony whereof I have hereunto set my hand in the presence of two subscribing witnesses.

WILLIAM S. PRIDE.
